UNITED STATES PATENT OFFICE.

WILLIAM M. CONNERY, OF PHILADELPHIA, PENNSYLVANIA.

REINFORCED FABRICATED METAL PLATE WALL SECTION.

Application filed December 21, 1921. Serial No. 523,922.

Heretofore in constructing large rooms, boxes, coal bunkers, coal cars and the like with fabricated metal sheets to form the walls of such structure, particularly where they are subject to internal and external pressure of any kind, whether it is from intense heat or from compacting the contents within the enclosure, the walls are not capable of giving or yielding to take care of such pressure. In such constructions, it is customary to fabricate the metal sheets by attaching them to heavy steel channels, angles, I beams, girders and the like which have appropriate flanges to receive the attaching means or rivets. These channels, angle irons, I beams, girders and the like are employed for the purpose of stiffening or reinforcing the wall, considerable reliance being at present invariably placed on a main I beam anchored at the top and bottom. In fact upon this I beam the safety of the entire structure depends.

However a construction of this character is not only clumsy and expensive, but is not at all expandible from heat, or capable of giving or yielding. Furthermore such walls for use in the construction of coal bunkers, rooms, boxes and the like are not practical, when made up in sections, and shipped to the place where the structure is to be installed, due to the I beams, channels or girders being heavy, which will make the freight rates a very large item in the cost of getting such fabricated wall sections to the place where they are to be used.

In building walls of such material, it is necessary to ship it in disassembled quantities, and when it reaches the various places where it is to be used, the work of constructing the wall entails considerable labor, due to the sheet sections being separably installed. Such walls are constructed with I beams arranged at right angles, intersecting each other, with the metal sheet sections connected to the I beams. Though there are no illustrations of this character of wall, it is possible to gather the foregoing method of construction, and therefore those interested in the art of reinforced fabricated metal sheet walls may readily understand the above disadvantages, and impractical features.

The present invention aims to embody a reinforcement of an expandible or yieldable character, though not necessarily, from portions of the fabricated sheets or metal plates

themselves, when fabricated as will be hereinafter explained and illustrated.

In adopting a reinforcement as made from the plates themselves, it is the aim to form the reinforcement by constructing corrugations in the plates at infrequent intervals, extending at right angles to each other, some being formed in succession, while others, as previously stated are infrequently arranged.

It is obvious that certain of the reinforcements or stiffeners of the fabricated metal plates of a wall section are rigid, while others are expansible, due to certain reinforcements extending at right angles to others. The reinforcements are formed of portions of the plates themselves standing out at variable distances, as nearly as possible at right angles to the plane of the wall section formed of such plates.

Still another purpose is the provision of a wall section made up of strong relatively thick metal plates or sheet metal material that often goes to waste in a plate shop because of its narrow width precluding its use in ordinary structures, and in this case the metal plates may not only be corrugated at infrequent intervals to provide an expandible or yieldable reinforcement, but may be fabricated together by expandible or yieldable reinforced connecting plates.

As a further purpose it is the aim to provide the wall section of fabricated plate metal, wherein expansion and contraction in a plane with the wall and lateral flexibility or yieldability is permitted, which expansion and contraction and lateral flexibility or yieldability is not present in the wall sections, wherein rigid I, channel and angle beams or girders are employed.

It is obvious that wall sections of the present character may be made in uniform shapes and sizes, permitting an entire wall to be fabricated thereby, and also it is to be observed that the wall sections are made up of fabricated plate metal of uniform width, capable of being stored in factory warehouses, as stock material, whereas the wall sections employing I, channel and angle beams or girders are incapable of being stored, in order to utilize a small space. Furthermore wall sections made up in this manner cannot be handled as easily as can the wall sections, wherein the expandible or yieldable reinforcements or stiffeners are employed.

A still further purpose is the provision of a fabricated plate wall section, wherein riveting and punching are very materially reduced, and in some instances eliminated 5 altogether, in view of the fact that the fabricated plate metal can be welded together, which is practically impossible where the wall sections are constructed with I, channel and angle beams or girders.

10 As previously stated the present construction of wall section insures a saving in weight alone, which permits an installation of such material in large projects at a relatively low cost, and this is especially true 15 when such materials are exported into foreign countries.

10 In constructing a wall section of the present character unlimited variations are thus secured with materials readily at hand and 20 very often of little value except as scrap.

25 Additionally the invention aims to provide a plurality of wall sections, wherein they may be united, either at right angles, or at obtuse angles, or in other positions, and in such cases may be welded in position, for the purpose of connecting the wall sections, which are also made up of fabricated plate metal having stiffeners of the present form.

30 In constructing wall sections of the present character, it is the aim to employ any suitable means, preferably forming dies shown in Letters Patent Nos. 1,534,299 and 1,535,295; and which dies are of such construction and shape as to form stiffening corrugations or reenforcement, such as illustrated, and which stiffening reenforcement may be used expansibly or rigidly, it depending entirely upon the relative arrangement 35 of the stiffeners or reenforcements.

40 It is to be understood that the particulars herein given are in no way limitative and that, while still keeping within the scope of the invention, any desired modifications of 45 details and desired proportions may be made in the apparatus according to circumstances.

45 The invention comprises further features and combination of parts, as will be herein-after set forth, shown in the drawings and 50 claimed.

55 In the drawings:

Figure 1 is a horizontal sectional view of the hull of a vessel, showing a series of coal bunkers or compartments made up of wall 55 sections;

Figure 2 is an enlarged sectional plan view of one of the bunkers;

Figure 3 is a sectional view on line 3—3 of Figure 2;

60 Figure 4 is a view in elevation of the outer wall of the bunker shown in Figure 2;

Fig. 5 is an enlarged detail perspective view of a wall section, showing fabricated metal plates attached sequentially by means 65 of welding and illustrating the fact that the

stiffeners or reenforcements or subpanel 7 is in the process of an accordion action, also showing in dotted lines the position of the main panels or metal plates assumed during this accordion action, the pressure being 70 in the direction of the arrow "b";

Figure 6 is a horizontal sectional view on line 6—6 of Figure 5;

Figure 7 is a vertical sectional view on line 7—7 of Figure 5;

Figure 8 is a view showing an obtuse angle joint between two wall sections, such as shown in Figure 5;

Figure 9 is a sectional view showing a right angle joint of two wall sections such as shown in Figure 5;

Figure 10 is a view in elevation of a wall section, wherein the metal plates are riveted;

Figure 11 is a sectional view on line 11—11 of Figure 10;

Figure 12 is a vertical sectional view on line 12—12 of Figure 10;

Figure 13 is a view showing an obtuse angle joint between two wall sections, of which the plate sections are riveted;

Figure 14 is a sectional view showing a modified construction, wherein two wall sections are united by a V-shaped stiffener, enabling the disclosed structure to expand or yield in either direction;

Figure 15 is a perspective view of a wall section showing an expansible yieldable joint thereof between the wall sections, wherein the joint is of a split character;

Figure 16 is an edge elevation of the structure shown in Figure 15; and

Figure 17 is a detail sectional view, wherein the stiffening members or reenforcements are formed in the paneled plate itself.

Fig. 18 is a view in perspective of a wall section showing the fabrication of metal plates and illustrating how the stiffeners 3, 10 and 11 are capable of accordion yielding action, to cause the stiffeners 10 and 11 to curve slightly as in full lines during such action with pressure in the direction of the arrow "a", and illustrating in dotted lines the normal shape of the stiffeners 10 and 11.

Fig. 19 is a rear view of such wall section, showing where the accordion walls of the stiffeners 10 and 11 are cut away at 7^a.

Fig. 20 is a view in perspective showing two wall sections fastened together, with the stiffeners 10 and 11 of one section at right angles to similar stiffeners of the other section.

Referring to the drawings, preferably Figures 1 to 8 inclusive 1 designates the wall section as a whole, which comprises a plurality of metal plates 2 or metal plate panels, which are provided with stiffeners 3 with accordion yielding walls, which are expansible or yieldable, so as to withstand internal and external pressure of any kind whether it is from intense heat, or as a result of com-

pacting the enclosure. These plates may be welded together as shown at 4 in Figures 1 to 7, or riveted together as at 5 as shown in Figures 10 and 12. These metal plates or panels are united by means of metal strip plates or sub-panels 6, 7 and 8, which may have one or a plurality of reenforcements or stiffeners with accordion yielding walls, such as corrugations 9, 10 and 11. The corrugations or stiffeners are to be formed in the plates or strips by any suitable means, preferably such as that embodied in the previously mentioned patents.

The metal strips which include the stiffeners or reenforcements 9, 10 and 11 have their edge portions welded at 12 to the plates 2, as in Figures 1 to 7 inclusive, or are riveted as shown at 13 in Figures 10 to 12 inclusive.

Obviously the ends of the stiffeners or reenforcements 3 are welded as at 14 to the stiffeners or reenforcements 9, 10 and 11, thereby permitting the wall sections to expand and contract in directions at right angles to each other.

It is well known that there is on the market a metal product, known commercially as corrugated sheet metal, therefore it is not the aim to claim the same in such terms as would broadly include corrugations in close succession, or commercially known sheet metal. The present form of wall sections are to be constructed of relatively thick metal plates, with the stiffeners, reenforcements or corrugations with accordion yielding walls and arranged at infrequent intervals in certain of the plates, whereas in connecting strip metal plates or sub-panels the stiffeners or corrugations are single, or several formed in succession. The stiffeners which are in succession may be at infrequent intervals. However the metal plate 6 has a single stiffener or corrugation, but of a larger size than those formed in the connecting strips 7 and 8. In fact the less stiffeners or corrugations, for instance one to be made in the plates 6 the larger they are to be constructed, and those connecting plates which have successive stiffeners or corrugations are to be used to form the side walls of a coal

bunker, box, room or the like, whereas the wall sections including connecting plates 6, each with a single corrugation are used for forming the corners or for connecting wall sections at obtuse angles, or may be used in the side walls of a coal bunker, to constitute the main expansible reenforcement or stiffener, to correspond with the main I or channel beam or girder, previously referred to as being used in the old construction. This main reenforcement or corrugation is anchored at the top and bottom, and upon this corrugation the safety of the whole structure may depend.

In Figures 8 and 13 the wall sections are arranged and connected at obtuse angles,

there being insert pieces 15 welded or otherwise secured in the adjoining ends of the corrugations or stiffeners, whereas in Figure 14 a relatively large expansible reenforcement or corrugation stiffening member 16 is used to connect the wall sections, enabling the wall sections to expand and contract, due to any internal or external pressure upon the wall.

By the construction in Figures 8, 13 and 14, the plates are deflected to arrange walls on an obtuse angle, and to provide a joined structure which is symmetrical and shapely, and at the same time to insure a closed and secure joint.

In Figures 15 and 16 the metal sheets or plates are fabricated in a different manner to those illustrated in the other figures. In fact the plates or sheets are joined by what may be known as a split indentation 17, which will permit the united plates to expand, yield or contract. In other words the edge portions of the plates are disposed at angles to the plane of the plates, and riveted or welded together as shown at 18 and 18^a Figures 15 and 16.

As previously set forth, and shown in Figure 17 the stiffeners or reenforcements in the form of corrugations are formed from the plates themselves, enabling the plates to contract and expand.

Though Figure 1 illustrates a series of coal bunkers of a vessel or ship made up of fabricated paneled wall sections, it is obvious that any form of compartment may be constructed, wherein there is internal or external pressure, or both, either caused by temperature conditions, or by some mechanical force. In fact the application of the wall sections is not to be limited to any particular form or structures. Coal bunkers on railroad cars may be built up by means of the wall sections, or ice bunkers may be constructed.

While Figure 2 discloses an enlargement of a coal bunker of the character shown in Figure 1, it is obvious that the construction in Figure 2 may be used to constitute a compartment of any character. However in this figure certain of the connecting plates are disclosed, for instance plates such as 6 and 7 having the V-shaped corrugations. The plates 6 are corners, while the plates 7 are intermediate corners. It will be noted that the wall sections in this figure are built up, so as to yield, expand and contract in either or both directions. In fact the flanges and those parts of the corrugations of the intermediate plates or the corner plates where the transverse corrugations 3 are welded to the plates 6 and 7, are cut away, enabling the walls of the compartment to yield or expand and contract in either or both directions, either as a result of internal or external pressure. This pressure may be cre-

ated through increased temperature, or by some mechanical force.

As shown in Figures 1 and 2 it will be seen that the inner and outer skins of the 5 wall of the ship or vessel has intermediate plates 6 including the corrugations 9, enabling the inner and outer skins to relatively yield, due to internal or external pressure.

10. In Figure 8 the wall sections are placed at an obtuse angle, showing inserts connecting the wall sections, the inserts being welded or otherwise connected, to permit the wall sections to yield or expand and contract.
15. It is obvious that these wall sections may be disposed at right angles as shown in Figure 9, or at any other angle.

As previously stated the flanges and those parts of the plates 6, 7 and 8 to which the 20 ends of the transverse corrugations or stiffeners 3 are connected by welding or otherwise are cut away, as clearly shown in Figures 7 and 8, enabling the wall sections to yield, expand and contract in either or both 25 directions.

Though it is essential to construct the wall sections to expand in either or both directions, it is also obvious that the flanges and those parts of the stiffeners or corrugations 30 of the plates 6, 7 and 8 to which the ends of the transverse corrugations are connected may remain intact, thereby reenforcing the wall section against expansion and contraction in one direction, whereas the 35 wall section is allowed to expand and contract in the other direction at right angles thereto, for instance as shown in Figure 12. While the wall section is reenforced against expansion and contraction in one direction 40 by the plates 6, 7 and 8, it is to be noted that these plates may be made to permit expansion and contraction in the direction of the plates, even though they are riveted.

It is also obvious that while the drawings 45 show the wall sections disposed whereby the plates 6, 7 and 8 are arranged vertically, it is clear that the wall sections may be disposed in horizontal directions, or arranged so that the plates 6, 7 and 8 may extend at 50 right angles to certain of the other wall sections, or at right angles to certain other plates 6, 7 and 8, so as to reinforce a compartment or coal bunker wall to a greater degree, than when the wall is made up of 55 wall sections capable of expanding and contracting in either or both directions. This is particularly true, if certain of the yieldable stiffeners of the wall sections are not cut away, at the point where the ends of the transverse corrugations 3 are welded to the 60 yieldable stiffeners.

It is also to be observed that though the wall section may be disposed so that its stiffeners may extend at right angles to other stiffeners, the entire wall may be al-

lowed to expand and contract in either or both directions, provided the corrugations of the plates 6, 7 and 8 are cut away where the transverse corrugations are welded thereto.

Where great rigidity is required a stiffening member may be introduced at the corners, instead of bringing the edges of the panelled plates or sheets together, and as previously stated the panels or metal plates 75 themselves may be formed into or provided with stiffening members, as shown clearly in Figure 17.

From the foregoing it is obvious that a wall may be constructed so that it may expand in one direction, and reenforced in the other direction, and vice versa, or reenforced in both directions, or made in order to expand and contract in both directions, as a 80 result of internal or external pressure, 85 whether caused by temperature conditions or by some mechanical force.

It is obvious that walls of different dimensions may be constructed, and furthermore the depth of the main corrugation 90 depends entirely upon the height as well as the width of the wall to be stiffened. In fact the reenforcement of the wall also depends upon the force of pressure, whether or not it is internal or external, and at what 95 point or location the pressure occurs. The construction and reenforcement of a wall including the present form of expandible stiffener also depends on whether or not the pressure is created by heat or cold, or by 100 some mechanical means or force. By referring to Fig. 18, it will be evident why the structure in the plate metal walls maintains an absolute plane surface, that is not warping irregularly under heat, and at the same 105 time provides sufficient stiffness to withstand the pressure in a direction at right angles to the plane of the wall and yet allow the walls of the stiffeners to have yielding 110 accordion action and permit a wall to expand and contract in various directions with the plane of the wall, when subjected 115 interiorly to heat, say 500° Fah., the sections illustrated in Figs. 18 and 19, preferably the former, may be taken from any wall having 120 an extent of ten times the portion illustrated. The actual distance between the points A—A and B—B on such figures, especially Fig. 18, may be taken as 36 inches. The expansion per degree Fah. of such an 125 area may be taken as .0000128 of an inch each inch per degree. In such case, the increase of distance between A to A for 500° 130 increase of temperature would be .2304. As this increase for the distance A to A (for 36 inches) may be taken from a running area of ten times that distance, the expansion will be 2.304 inches. The expansion 135 invariably tends to close the angle contained within the stiffener or indentation, and this

applies throughout the whole structure, except at the periphery where there must be, at each edge, a resistance equal to the resisting tendency of one rib to bending under interior heat of 500° Fah. The indentation or stiffener fulcrums at its peak, swings at what might be called the base of the triangle, indicated at point *c* on Figs. 18 and 19. The ease with which the sides of the indentation or stiffener approach each other increases with the increase due to expansion of length of the flat surface between the indentations. The greater the heat, the more the flat surface expands and the more flexible the indentation or stiffener becomes to absorb what little stress the increase of depth of the flat portion produces. It is evident that the junction between the crossing indentations partakes proportionately of the general movement of the sides of the indentations towards one another.

With regard to coal bunkers, as in Figs. 1 and 2, it is obvious that a vessel is subjected to considerable vibration due to the 25 throb or pulsation of the engine and its attendant cooperating elements, in view of which the coal would compact thereby causing internal strain or pressure of the walls of the bunker; and since the stiffeners have 30 accordion yielding opposed walls, the side walls of the coal bunker will give or yield and thereby permit expansion and contraction in various directions.

Referring to Fig. 7, which is a sectional view on line 7—7 of Fig. 5, it is to be noted that where the stiffeners 3 are electrically welded to the accordion walls of the stiffeners 10 and 11 of the metal strip plates 7, 8, and 9, the metal of such accordion walls 40 is cut away, as shown more clearly at 7^a in Fig. 19. Also, referring to Fig. 6, it will be observed that the stiffeners extend to the peak of the accordion walls of the stiffeners 11 of the metal strip plate 8. This arrangement, together with the cut-away portions of such accordion walls, permit the plate metal panels to expand yieldably and then yieldably return to normal shape, due to the internal pressure derived from the 50 fluctuation of intense temperature or heat on the interior of a structure having such walls. The stiffeners of the metal strip plates will also have accordion-yielding action which, with the accordion yielding action of the stiffeners 3, enable the wall construction in Figs. 2, 5, 18, 19, 20 and 21 to expand and contract in various directions with the plane of the wall construction.

This yieldable expansion and the return 60 to normal condition takes place due to internal pressure caused by enormous compacting, or compacting heavy weight against the interior surface of the wall construction. In Fig. 18, the stiffeners of the metal strip 65 plates are in the act of an accordion yield-

ing action, as shown, due to one set of stiffeners 3 assuming an angle to the other set of stiffeners 3. During such accordion action, the bases of the triangles of the stiffeners of the metal strip plates widen. In 70 other words, as the accordion walls of the stiffeners 3 are so functioning, the bases of the triangles of the stiffeners 3 are widened, while the stiffeners 10 and 11 of the metal strip plates assume a curvature, clearly 75 shown in Fig. 18. The wall constructions in Figs. 18 and 20 may be turned around so that the stiffeners 3 may assume vertical positions in which case a wall construction of great extent may be so used and 80 installed. From the foregoing, in connection with Figures 2, 5, 18, and 19, it is clear, the wall construction or wall sections may expand and contract in various directions through the plane of the wall construction. 85

The invention having been set forth, what is claimed is:—

1. A wall section composed of fabricated metal sheets, said sheets having reenforcements formed from the plates themselves, 90 said plates being united in sequence extending in one direction, and sheet metal strips connecting the plates in directions at right angles to the first connections between the plates, said connecting strips having expandable reenforcements, thereby reinforcing the wall section.

2. In a wall construction for the purpose indicated, a pair of wall sections, each composed of fabricated metal panels, said wall sections having reenforcements intersecting each other at right angles, certain of said reenforcements connecting certain adjacent edges of some of the panels, and means inserted and welded into the adjacent ends of 105 the reenforcements of the two wall sections, thereby connecting the wall sections.

3. In a compartment having its walls fabricated with wall sections, stiffeners connecting the fabricated wall sections at the 110 corners of the compartment, each wall having right angle arranged stiffeners, the right angle arranged stiffeners of each wall being relatively smaller than the corner stiffeners.

4. In a compartment having its walls fabricated with wall sections, stiffeners connecting the fabricated wall sections at the corners of the compartment, each wall having right angle arranged stiffeners, the right angle arranged stiffeners of each wall being relatively smaller than the corner stiffeners, certain of said stiffeners being expandable in one direction, said right angle 120 stiffeners having stiffening elements proper greater in number than the corresponding elements of the corner stiffeners, and means for fastening the wall sections and the stiffeners fabricated together.

5. A manufacture comprising a wall sec- 125

- tion composed of main plate metal panels provided with stiffening corrugations arranged at infrequent intervals and lying in a plane normal to the panels, sub-panels 5 having stiffening corrugations arranged in consecutive frequent intervals and likewise lying in the normal plane of the sub-panels, the fabrication of the main and sub-panels being such that the corrugations connect and 10 are at right angles to each other, thereby reinforcing the structure.
6. As an article of manufacture, a compartment wall provided with main stiffeners lying in one direction with the plane of the 15 wall and provided with relatively smaller parallel spaced stiffeners, the latter being in spaced groups parallel with the main stiffeners, said wall having additional auxiliary spaced stiffeners at right angles to the main 20 and relatively small stiffeners, certain of the additional stiffeners connecting the stiffeners of said groups and also connecting with the main stiffeners.
7. A wall section, comprising a plurality of metal plates having reenforcements formed from the plates themselves said plates being attached in sequence arranged in one direction, said reenforcements having walls yieldable expansibly and contractibly 30 in a plane in one direction in the plane of the wall section, strip metal plates attached to the first plates in directions at right angles to the first attachments, said strip metal plates having reenforcements provided with 35 walls adapted to yield expansibly and contractibly in the plane of the wall section.
8. A wall construction consisting of wall sections being attached sequentially in various directions in the plane of the wall, each 40 section comprising a body provided with reenforcements lying horizontally and vertically, the horizontal reenforcements having accordion walls yieldable in the plane of the wall construction, said vertical reenforce- 45 ments having accordion walls yieldable in the plane of the wall construction, the yielding walls of the horizontal and vertical reenforcements constituting means whereby the wall construction may expand and con- 50 tract in various directions in the plane of the wall construction and at right angles to the plane of the wall construction.
9. A compartment wall having main stiffeners lying in one direction with the plane of the wall provided with relatively smaller parallel spaced stiffeners, the latter being in spaced groups parallel with the main stiffeners, the main and relatively smaller stiffeners having opposed walls to yield in the plane 60 of the compartment wall, said compartment wall having additional auxiliary spaced stiffeners at right angles to the main and the groups of relatively small stiffeners, said additional auxiliary stiffeners having op- 65 posed walls to yield in the plane of the com- partment wall, certain of the additional stiffeners connecting certain of the stiffeners of said groups and also connecting with the main stiffeners of said groups.
10. In a wall construction for the purpose indicated, a pair of wall sections composed of metal plate panels being sequentially attached, yielding means for uniting the panels, said panels having means consisting of stiffeners provided with opposed yieldable 70 walls thereby permitting expansion and contraction in directions at right angles in the plane of the wall construction, and means for uniting the adjacent edge portions of the wall sections.
11. In a wall construction for the purpose indicated, a pair of wall sections composed of metal plate panels being sequentially attached, metal strip plates for uniting the panels and provided with accordian 75 yieldable walls permitting expansion and contraction in one direction in the plane of the wall construction, said panels having stiffeners provided with opposed walls yieldable in the plane of the wall construction 80 thereby permitting expansion and contraction at right angles to the first expansion and contraction.
12. In a wall construction for the purpose indicated, a pair of wall sections composed of metal plate panels being sequentially attached, metal strip plates for uniting the panels and provided with accordian yieldable walls permitting expansion and contraction in one direction in the plane of the wall construction, said panels having stiffeners provided with opposed walls yieldable in the plane of the wall construction 85 thereby permitting expansion and contraction at right angles to the first expansion and contraction.
13. In a wall construction for the purpose indicated, a pair of wall sections each composed of metal plate panels being sequentially attached and provided with stiffeners at infrequent intervals, the stiffeners having accordian yieldable walls permitting expansion and contraction in a direction in the plane of the wall construction, and yieldable means connecting the panels to make up the fabrication of the wall construction.
14. In a wall construction for the purpose indicated, a pair of wall sections each composed of fabricated metal plate panels being sequentially attached provided with stiffeners at infrequent intervals, and means for connecting the plate panels to make up the fabrication of the wall construction, said panels and said means provided with stiffeners having accordian yieldable walls permitting expansion and contraction in various directions in the entire plane of the wall construction.
15. A manufacture comprising a wall sec- 120
- 125
- 130

tion composed of main plate metal panels provided with stiffening corrugations lying in a plane normal to the wall section, sub-panels having stiffening corrugations likewise lying in a plane normal to the wall section, the fabrication of the main and sub-panels being such that the corrugations connect and are at right angles to each other thereby reenforcing the structure, the stiffening corrugations of the main sub-panels having opposite yieldable walls allowing expansion and contraction in the plane of the wall section.

16. A compartment structure including a wall section composed of main plate metal panels provided with stiffening corrugations lying in a plane normal to the wall section, sub-panels having stiffening corrugations likewise lying in a plane normal to the wall section, the sequential attachment of the main and sub-panels being such that the corrugations connect and are at right angles to each other thereby reenforcing the structure, the stiffening corrugations of the main and sub-panels having opposite yieldable walls allowing expansion and contraction in various directions in the plane of the wall section, and means for uniting a pair of such wall sections together.

17. In a wall construction for the purpose indicated, a pair of adjoining wall sections each having reinforcements intersecting each other at right angles provided with accordion opposite walls yieldable expansibly and contractibly, thereby permitting expansion and contraction in various directions in the plane of the wall, and means inserted between and fastened to the adjacent ends of the reinforcements of the two wall sections, thereby uniting the wall sections and permitting them to further expand and con-

tract incident to internal and external pressure.

18. In a wall section, the combination with metal plates being attached vertically in the plane of the wall section to compose the wall section, said plates having infrequently arranged horizontal stiffeners with accordion opposite walls yieldable expansibly and contractibly in the plane of the wall section, of perpendicular stiffeners with accordion opposite walls yieldable expansibly and contractibly and connecting the adjacent edges of the plates and the adjacent ends of the first stiffeners, the accordion yielding walls of both sets of stiffeners constituting means whereby the wall section may expand and contract in various directions in the plane of the section.

19. In a wall section, the combination with metal plates being attached vertically in the plane of the wall section to compose the wall section, said plates having infrequently arranged horizontal stiffeners with accordion opposite walls yieldable expansibly and contractibly in the plane of the wall section, of perpendicular stiffeners with accordion opposite walls also yielding expansibly and contractibly and connecting with the adjacent edges of the plates and the adjacent ends of the first stiffeners, the accordion yieldable walls of both sets of stiffeners constituting means whereby the wall sections may expand and contract in various directions in the plane of the section, the accordion yieldable walls varying in number in a horizontal direction in the plane of the wall section.

In witness whereof, the inventor's signature is hereunto affixed.

WILLIAM M. CONNERY.
